CONSTANT PERIODIC MOTION DEVICE

Jacob Rabinow, Takoma Park, Md.

Application May 25, 1955, Serial No. 510,941

9 Claims. (Cl. 58—29)

This invention relates to high precision timepieces of the gravity pendulum type and, more specifically, to a type of pendulum which is driven by another pendulum through a servo system.

It is well-known that pendulum clocks of extremely high precision have been built but even in the best of these it has not been possible to eliminate the effects of the variations in the driving impulses delivered to the pendulum and of the friction in the suspension. The fact that spring suspensions are used does not completely eliminate friction because of hysteresis in the spring. It is the purpose of this invention to eliminate or greatly reduce both the effects of the driving mechanism on the pendulum and of the variations of the friction in the suspension of the pendulum.

The specific nature of the invention, as well as other objects and advantages thereof, will clearly appear from a description of a preferred embodiment as shown in the accompanying drawing, in which:

Fig. 1 is a schematic diagram showing the basic arrangement of my double pendulum clock, partly in section; and

Fig. 2 is a side view of the double pendulum clock and some additional details.

The pendulum 2 is contained within another pendulum 3 and the two swing together as will be described below. The axes of the two pendulums are made colinear. This can be done in many ways, but the method shown is to hang the outer pendulum on two knife edges 4, 6. The inner pendulum is hung on another knife edge 7 and the axes of rotation of both sets of knife edges are made as closely aligned as possible. The outer pendulum is provided with two small windows near its lower end shown at 8 and 9. These windows are so located that when the inner pendulum and the outer pendulum hang still, the windows are just half covered by the bob 11 of the inner pendulum.

The periods of the two pendulums are independently made to be as nearly equal as possible. The outer pendulum is driven by the best available means, for example, such as described in Dr. Rawlin's book on "The Science of Clocks and Watches," second edition, page 108. Schematically the mechanism is shown in Fig. 1.

The outer pendulum is driven by an unbalanced weight 15 pivoted about the point 12. As the pendulum swings to the right as seen in Fig. 1, it contacts the lower end of this weight, closing the circuit through the battery and the two electromagnets 13 and 14 (see Fig. 2). Prior to this instant, the rocking armature of the solenoid was held against the pin 17 by the action of the spring 18. For this purpose the outer casing of outer pendulum 3 is assumed to be made of conducting material, although in practice it would probably be preferable to specially form the circuit closing path of the pendulum as a switching strip attached to the pendulum. It will be understood that points x—x in Fig. 1 are connected to points x—x

in Fig. 2, in accordance with usual circuit drawing practice. The pendulum touching the unbalanced weight 15 not only closes the circuit by direct contact, as mentioned earlier, but also lifts the right hand supporting finger 19 of this weight from the platform 21. The current flowing through the solenoid 13 tilts the platform into the position shown in Fig. 1. The pendulum continues its swing to the right, comes to a stop and then begins its swing to the left. The contact between the pendulum 3 and the weight 15 will be broken at a point later in the cycle than it was made. Or in other words, the weight will stay in contact with the pendulum for a longer time on the down stroke than it was on the up stroke. This imparts energy to the pendulum and maintains its oscillations. After the contact is broken, the solenoid 13 releases, permitting the armature 21 to swing against the pin, lifting the unbalanced weight and thus recocking it for the next cycle.

It will be obvious to those versed in the art of such mechanisms that if the outer pendulum is caused to swing, the inner pendulum will begin to swing also, due to the coupling between them produced both by the air contained in the outer pendulum and by the very small friction in the inner bearings. Even if the outer pendulum were completely evacuated and no air coupling were present, the small amount of friction inevitably present in the suspension of the inner pendulum would cause this pendulum to oscillate at some time after the outer pendulum were started. Methods of locking both pendulums together at the start can, of course, also be used but have no significant bearing on the crux of this invention. A photocell 22 and a source of light 23, which may be an electric light bulb, are mounted on opposite sides of the main pendulum as shown in Fig. 2. If both pendulums swing in exact synchronism, the windows will be half covered by the bob of the inner pendulum and a small amount of light would reach the photocell if the light bulb were energized. The light bulb is controlled by a cam wheel 24 which is operated by electromagnet 14 connected in series with the electromagnet 13 that operates the mechanism driving the outside pendulum. A pawl spring 25 advances the cam wheel 24 one tooth each time the magnet 14 is energized. It will be seen that during every stroke of the pendulum 3, as its electromagnet moves the armature 21, the cam wheel is advanced one step. During the motion of the cam wheel the contact 26 closes and opens, thus lighting the bulb once per complete oscillation of the pendulum. By properly locating the cam follower with respect to the cam wheel, the light bulb can be made to light at approximately the time when the outside pendulum swings through its neutral point. It will be seen that the contact is closed only when the pendulum swings in one direction. The timing of the light is not critical since the phasing of the pendulum does not change appreciably through a small portion of any one stroke.

The light falling on the photocell produces a current impulse in the latter which is fed to the amplifier 27, points Y—Y of Figs. 1 and 2 being connected in the same circuit. The amplifier is so arranged that it produces an output which is substantially a direct current whose value is proportional to the intensity of the pulses. Means for producing a smooth direct current whose intensity varies with the intensity of the pulsed input of the amplifier are well-known to the electronic art and are described, for example, on pages 482-500 of "Radio Engineering" by Terman, 2nd ed. (McGraw-Hill). The direct current of the amplifier 27 is fed to a balanced armature relay 28 whose other side is biased by direct current such as obtainable from a battery 29. The relay 28 is a single-pole double-throw relay which stays in "neutral" when the currents through its two windings are equal.

A direct current, reversible, motor 31 is connected to the output of relay 28 and is arranged through gearing 32 to raise and lower a small permanent magnet 34 mounted below the outside pendulum. A small piece of magnetic material 36 is shown mounted on the pendulum. It will be seen that the position of the permanent magnet will affect the rate of the pendulum. Weight 37 is located near the bottom of pendulum 3 so that the centers of gravity of both pendulums are substantially coaxial.

It is now obvious that by proper adjustment of the output relay currents in relay 28, the condition can be set up where if the two pendulums move in unison, the intensity of the light pulses falling on the photocell will be such as to produce equilibrium in the output relay and keep the motor from turning. If the outer pendulum is not in phase with its inner counterpart, the light pulses will be either larger or smaller depending on the phase relationships of the two pendulums, the currents in the output relay will be unbalanced, the motor will run in the appropriate direction to change the rate of the outer pendulum and bring the two pendulums into synchronism again. By making the windows in the outer pendulum very narrow the sensitivity of such a device can be made very high. The mechanical arrangement of the magnetic speed adjustment is such as to cause very slow changes in the rate of the outer pendulum so that small perturbations in the oscillations of the two pendulums would have little effect on the overall adjustment.

It is obvious that the amplitude of the oscillations of the outside pendulum can be varied, if desired, by means well-known to the art. One method of accomplishing changes in amplitude would be to move the position of the stop pin 17 so as to increase or decrease the energy imparted to the outer pendulum during each cycle.

It will be seen that if the two pendulums are moving in exact synchronism the inner pendulum experiences negligible losses. It moves in unison with the outer pendulum and, if the outer pendulum is evacuated, there are no losses due to air friction. Even if the outer pendulum were not evacuated, the losses due to air friction would be greatly reduced because both pendulums are swinging together carrying the air with them. The air losses would be merely due to some secondary circulating currents. In electrical terms, therefore, the losses of the inner pendulum are much reduced, its *Q* is greatly increased, and its accuracy should be proportionately improved. If one assumes, for example, that the two pendulums move one inch at their lower extremity and if one assumes further that the servo system is good enough to keep them in step within 0.001 of an inch, then the losses of the inner pendulum are reduced by a factor of the order of 1000 and its "Q" increased several orders of magnitude.

It is obvious that the method of reducing losses by driving the bearings of a moving member in synchronism with the member are also applicable to devices other than a gravity pendulum. It should be recognized that the use of the outer pendulum is merely a convenient way of oscillating the knife edge bar supporting the inner pendulum.

While the suspension described so far is of the knife edge variety, I do not intend to be limited by this description. Either pendulum can be suspended by a spring or any other device without departing from the sense of my invention. While it is desirable to keep the axes of rotation as nearly colinear as possible, slight deviation from this can be tolerated because the effect of such small deviation would be to merely cause the inner

pendulum to move a very small amount vertically as the two pendulums swing from side to side.

It will be apparent that the mechanism shown may be incorporated into a clock or other timepiece as the time reference element thereof, e. g., the outer pendulum 3 may be substituted for the pendulum of any pendulum-controlled clock.

It will be apparent that the embodiment shown is only exemplary and that various modifications can be made in construction and arrangement within the scope of my invention as defined in the appended claims.

I claim:

1. A mass mounted on an axis for periodic motion about said axis, a bearing supporting said mass for said motion, said bearing comprising a supporting portion movable about said axis with respect to said mass, means for imparting periodic motion to said supporting portion about said axis, means for sensing the periodic motion of said mass without appreciably disturbing said motion and producing signals related to said motion, and means controlled by said signals for maintaining the periodic motion of said supporting portion synchronized with the periodic motion of said mass to minimize relative motion between said bearing portion and said mass.
2. The invention according to claim 1, said mass being a pendulum.
3. The invention according to claim 2, said means for sensing comprising an optical sensing system.
4. A pendulum, suspension means for said pendulum, independently movable secondary suspension means containing said first suspension means, sensing means to detect the oscillations of said pendulum, means actuated by said sensing means to actuate said secondary suspension means to move in synchronism with said first suspension means so as to reduce the losses in said first suspension means.
5. In a timing device, a time reference means consisting of an oscillating member, supporting means for said oscillating member free to oscillate in unison with the oscillations of said oscillating member, means to oscillate said support means, and further means to detect the motion of said oscillating member and to oscillate said support means in phase with said oscillating member.
6. In a timing device, a periodic actuating means, a first pendulum driven by said means, a second pendulum supported for independent oscillation by said first pendulum, means for detecting differences in motion between said pendulums, and means controlled by said detecting means for affecting said periodic actuating means to maintain a constant phase relationship between said pendulums.
7. The invention according to claim 6, said second pendulum being mounted within said first pendulum.
8. The invention according to claim 7, said first pendulum totally enclosing said second pendulum.
9. The invention according to claim 6, said means for detecting differences comprising photoelectric means.
